ATTORNEY

UNITED STATES PATENT OFFICE.

FREDERICK L. SCHLEY, OF BROOKLYN, NEW YORK.

PRINTER'S GALLEY.

1,389,223.

Specification of Letters Patent. Patented Aug. 30, 1921.

Application filed January 16, 1920. Serial No. 351,797.

To all whom it may concern:

Be it known that I, FREDERICK L. SCHLEY, a citizen of the United States, and a resident of the borough of Brooklyn, county of 5 Kings, city and State of New York, have invented certain new and useful Improvements in a Printer's Galley, of which the following is a specification.

The present invention relates to an improved printer's galley, and has particularly for an object to provide a galley in which the blocks or forms of set-up type may be placed in such manner as to be solidly and rigidly supported at all sides so that 10 displacement of the type and "pieing" of the form will be prevented. When placing a form of type in a galley, the same is tied about by a binding cord which forms a projection or ridge about the periphery of the 15 form, and which in the usual form of galley spaces the sides of the type from the walls of the galley, and being yieldable will permit displacement of the type, and especially the smaller sized outside type will in some instances become twisted about or otherwise 20 displaced.

According to the present invention, I propose to provide a galley having in its side walls a groove or channel for receiving the 25 binding cord, to the end that the sides of the type form will fit snugly against the sides of the galley and will therefore be supported against displacement. A further object is to provide a galley which may be 30 easily lifted, the outside rib produced by the formation of the interior grooves constituting a finger hold, and which will be substantially rigid against bending and distortion, the rib or groove stiffening the side 35 walls.

With these and other objects in view, embodiments of my invention are shown in the accompanying drawings, and these embodiments will be hereinafter more fully described with reference thereto and the invention will be finally pointed out in the 40 claims.

In the accompanying drawings,

Fig. 1 is a perspective view of a galley 45 according to the present embodiment of my invention, and showing a form of type set therein;

Fig. 2 is a similar view of the galley with the type removed;

Fig. 3 is a transverse vertical sectional

view through the galley and showing the type therein;

Fig. 4 is a similar view of a modified form of construction; and

Fig. 5 is a similar view of a further modified form.

Similar reference characters indicate corresponding parts throughout the several figures of the drawings.

Referring to the drawings, and more particularly to Figs. 1 to 3 thereof, the embodiment of my invention shown therein comprises a sheet metal base plate 10 having side walls 11 and 12, and an end wall 13 bent upwardly therefrom and connected at the 70 corners by means of extensions 14 at the ends of the side walls, bent over exteriorly upon the end wall and secured by rivets 15.

A groove or channel 16 is formed interiorly of the said side and end walls substantially centrally of the longitudinal edges of the same of sufficient depth and width to receive the binding cord 17 of the type form 18, the sides of the type form fitting snugly against the inner sides of the said walls. 80

The formation of the groove produces a rib 19 exteriorly of the walls, which may serve as a convenient finger hold in lifting the galley, it being understood that the type form is quite heavy.

Adjacent the base plate, the end and side walls are provided with a recessed portion 20 to permit of drainage of a cleansing fluid when applied to the type, and also to receive dust or other matter settling upon the 90 base plate and which would otherwise be forced into the corners and prevent snug fitting of the type form.

In Fig. 4, I have illustrated a slightly modified form of construction in which the 95 side and end walls 21 are formed of separate strips of material from the base plate 22, and are provided with lateral flanges 23 and 24, a longitudinal groove 25 therebetween and a recessed portion 26 adjacent the base 100 plate, the flange 23 being secured to the base plate by rivets 27, the upper flange 24 forming a rest to permit of the piling up of a number of galleys, one upon the other.

In the form illustrated in Fig. 5, the side 105 walls are formed of solid strips 28 preferably of cast metal, secured to the base plate by elongated rivets 29 extending therethrough and having a binding cord receiving longitudinal groove 30 formed along its 110

inner side, and a rib 31 formed along its outer side, while adjacent the base plate there is provided a dust receiving groove 32.

The galley according to my invention, is 5 of simple and inexpensive construction, will not easily bend or become distorted, and supports the type form in a manner as to prevent the same becoming disarranged, the sides of the type fitting snugly against the 10 inner sides of the galley.

I have illustrated and described preferred and satisfactory embodiments of my invention, but it is obvious that changes may be made therein within the spirit and scope 15 thereof as defined in the appended claims.

I claim:

1. A printer's galley comprising a bottom, sides and an end, the sides and end being formed with an outwardly-set portion at an 20 elevation above the bottom whereby a groove is produced on the interior of the galley in position to receive the binding cord of a

form of type and a rib is provided on the exterior of the galley.

2. A printer's galley comprising a base 25 plate, end and side walls extending therefrom, said walls at the base plate providing an internal groove, said walls provided with a second groove at an elevation above the base plate necessary to receive the binding 30 cord of a form of type, and means on the exterior of said walls spaced above the base plate for receiving the fingers in lifting and handling the galley.

3. A printer's galley comprising a base 35 plate, side walls provided interiorly with a longitudinal groove adapted to receive the binding cord of a form of type placed in said galley, and a longitudinal rib exteriorly 40 of said side walls.

In testimony that I claim the foregoing as my invention, I have signed my name hereunder.

FREDERICK L. SCHLEY.
